John Dilworth

BY THEIR ATTORNEY. - Walter Gunn.

UNITED STATES PATENT OFFICE.

ALFRED EDWIN HUGHES AND JOHN DILWORTH, OF STOCKPORT, ENGLAND.

RADIATOR TUBE.

1,412,056.

Specification of Letters Patent. Patented Apr. 11, 1922.

Application filed March 15, 1920. Serial No. 366,045.

To all whom it may concern:

Be it known that we, ALFRED EDWIN HUGHES and JOHN DILWORTH, both subjects of the King of Great Britain and Ireland, 5 and residents of Stockport, England, have invented certain new and useful Improvements in or Relating to Radiator Tubes, of which the following is a specification.

This invention relates to radiators and the 10 like and has for its object to provide improved means for securing the tubes in position.

According to the invention the radiator or 15 like casing is provided with a plurality of nipples at one part and a further and like plurality of nipples at another part. Engaging such nipples is a plurality of tubes 20 each of a length suitable for engaging the sets of nipples, and each being conical at one end and having a yieldingly mounted 25 jointing ferrule at the other end, or each having a yieldingly mounted ferrule at both ends, whereby water-tight joints can be made between the tube ends and nipples, the tubes being removable and replaceable at will by 30 hand, no soldering or brazing being required.

The invention will be more particularly 35 described by the aid of the accompanying drawings, wherein:

Fig. 1 is a radiator showing the tubes in position.

Fig. 2 is a detail view drawn to an enlarged scale of one of the radiator tubes 35 in position.

Fig. 3 is a sectional view of Fig. 2.

Fig. 4 shows the parts ready for assembling and

Fig. 5 is a sectional view with one end 40 of the tube in position in the act of assembling the parts.

Referring to the drawings, the bottom part *a'* of the radiator casing *a* is provided with a series of internally coned nipples *b* 45 to receive the coned ends *c'* of the radiator tubes *c*, a packing ring *d* of rubber or other suitable material being interposed to ensure a liquid tight joint. To the top *a²* of the radiator casing *a*, a second series of internally 50 coned nipples *e* are secured, the internal diameter of the bottom end of which is equal to the external diameter of the tube *c*, and sufficiently large to allow the same to pass there-through. The opening is coned, the internal diameter at the top being larger than the external diameter of the tube to allow

the latter to tilt for a purpose hereinafter explained.

Slidably mounted at the top of the tube *c* is a ferrule *f*, the top of which is recessed at *f'* to receive a packing ring *g*. The ferrule *f* is normally forced towards the end of the tube *c* by means of the spring *h*, which reacts against the collar *i* secured to the tube *c*. 65

When assembling the parts the top end of the tube is placed in the lower end of the nipple *e* and forced upwards against the pressure of the spring *h* until the end *c'* of the tube *c* is above the top of the nipple *b* 70 as seen in Fig. 5, the conical conformation of the nipple allowing the necessary tilting of the same. The tube is now moved into axial alignment with the nipples and when released the spring *h* forces the coned end 75 downwardly to form a liquid tight joint with the nipple *b*. At the same time the upward pressure of the spring *h* forces the ferrule upwards to exert pressure on the packing ring *g* which is compressed against the 80 end of the nipple *e* so as to expand and form a liquid tight joint for the top end of the tube *c*.

If desired the spring *h* may be arranged on or in the nipple *e* and a ferrule or washer 85 provided to make joint with the end of the tube *c* or a collar thereon. It is preferred to arrange the yielding spring at the top of the tube so that it is not affected by the weight of the tube when sudden shocks or 90 jars take place but it will be understood that if desired said yielding joint may be arranged at the bottom of the tube.

By these means the necessity for soldered joints is dispensed with and the tubes can 95 not only be readily assembled but can be readily removed and replaced when desired in the event of stoppage or from other causes, and as the joint can yield against the pressing of the spring when temperature 100 variations cause contraction or expansion of the parts a perfect joint is maintained for an indefinite period.

As a further modification the tubes may be the same at both ends and be fitted with 105 the ferrule, collar and spring at both ends.

What we claim is:-

1. A radiator comprising a casing, together with tubes each provided with a ferrule slidably mounted thereon and a spring 110 to force the same outwards, one end of each of said tubes being adapted to enter sockets

in the radiator while the other end is adapted to enter a hole in a nipple on the radiator said hole being larger in diameter than the external diameter of the tube and the arrangement being such that one end of the tubing is adapted to enter said hole against the pressure of the spring and be subsequently moved into axial alignment with the seating for the other end of the tube the spring acting to maintain a liquid tight joint at both ends of the tube, substantially as described.

2. A radiator comprising a casing, a plurality of nipples secured to one part of the casing and a further and like plurality of nipples secured to another part of the casing, a plurality of lengths of tubing and each length of tubing at one end being conical, and at the other end having a fixed collar and a loose ferrule, and means for yieldingly holding the ferrule and tube in engagement with the nipples, substantially as herein set forth.

3. A radiator comprising a casing, a plurality of nipples secured to one part of said casing, and each nipple having a conical interior, the narrowest part being furthest

from that part of the casing to which the nipple is secured, a further and like plurality of nipples secured to another part of the casing, and each having a conical interior with the narrowest part nearest that part of the casing to which the nipple is secured, and a plurality of lengths of tubing each being formed conical and having a packing ring at one end and a fixed collar at the other end, a loose ferrule, with packing ring, and a spring between the collar and ferrule, each length of tubing being long enough to project through the ferrule the conical interior of which is narrowest at the end furthest from the radiator casing, the conical end of each length of tubing fitting the nipple the conical interior of which is narrowest at the end next the casing, substantially as herein set forth.

In witness whereof we have hereunto set our hands in the presence of two witnesses.

ALFRED EDWIN HUGHES.
JOHN DILWORTH.
